UNITED STATES PATENT OFFICE.

JOHN I. STEEN, OF WAUKEGAN, ILLINOIS.

LOCK.

1,351,806.

Specification of Letters Patent. Patented Sept. 7, 1920.

Application filed November 5, 1917. Serial No. 200,337.

To all whom it may concern:

Be it known that I, JOHN I. STEEN, a citizen of the United States, residing at Waukegan, in the county of Lake and State 5 of Illinois, have invented certain new and useful Improvements in Locks, of which the following is a specification.

This invention relates to improvements in locks of the keyless type and one object is 10 to provide a lock of this class adapted particularly for use on trunks, suit-cases, traveling bags and the like although the lock is capable, as well, of a very general use. A further object is to provide a lock of this 15 type that is neat in appearance, simple in construction since it is composed of few parts, and that is cheap to manufacture, and that will not become locked in open position.

20 With the foregoing and other objects in view the invention consists in the construction and novel combination and arrangement of parts hereinafter fully described, illustrated in the accompanying drawing 25 which forms a part of this specification, and pointed out in the claims hereto appended, it being understood that various changes in form, proportion, and minor details of construction may be resorted to 30 without departing from the spirit or sacrificing any of the advantages of the invention.

In the drawing:

Figure 1 is a face view of my improved 35 lock.

Fig. 2 is an edge view of the same in open position and partly in section to afford a better illustration.

Fig. 3 is a sectional fragmentary plan 40 view of the interior of the lock, taken on line 3-3 of Fig. 2, but with one washer omitted to disclose the top tumbler more clearly.

Fig. 4 is a view similar to Fig. 3, the aforesaid washer being included, but with 45 the movable parts in an altered position.

Fig. 5 is a sectional view of the indicator.

Fig. 6 is a section on line 6-6 of Fig. 3.

Like reference characters denote corresponding parts throughout the several 50 views.

The reference numeral 1 denotes an anchor plate designed to be secured by the screws 2 to the body portion 3 of the trunk or other article to be locked. To the plate 1 55 a leaf 4 is secured by hinge 5, the free end of said leaf being formed with a flat rounded

portion 6 whereon the numbered graduations 7 are formed and in which the spaced apertures 8 are formed. A peripheral rib 9 is formed about the flat portion 6 to afford 60 protection for an indicator 10 which is adapted for registration with the graduations 7 and which extends through an enlarged opening 11 formed centrally of said flat portion 6 to permit liberal relative 65 movement of said indicator. The indicator 10 is a hollow member, circular in cross section and closed at one end and formed of two concentric detachable cup-shaped portions, one of said portions being formed 70 with the flange 13 and the other with the terminal flange 12 from which the lug 14 is bent, said flanges being positioned upon opposite sides of the flat portion 6.

A plate 15 provided with lateral wings 16 75 is secured to the trunk top thereby, said plate being formed with a circular central depression 17 and with an outer rounded edge 18. An inverted U-shaped yoke 19 has its ends secured in the bottom of the depression 17 and its base spaced above the said depression, said yoke extending through an aperture 20 in the bottom of a casing 21 which casing is circular in shape and adapted to fit inside the depression 17, said yoke 19 80 permitting limited play of said casing but preventing rotation of the same within said depression. The casing 21 is provided with a sight perforation 21^a and is formed along its upturned rim with the spaced lugs 22 90 adapted for insertion in the apertures 8 of the rounded portion 6 of the leaf 4 whereby said casing and leaf are releasably secured together. An anchor lug 23 secured to the rim of the casing diametrically opposite the 95 yoke 19 extends inwardly toward said yoke. A circular tumbler casing 24 is formed with the diametrically opposed openings 25, 23 in its wall, an extension 27 of said casing 24 registering with the opening 26, said extension being adapted for insertion in the yoke 19. The base of the tumbler casing is formed with the notch 28 in the plane of the wall-opening 25, said notch 28 being smaller than the said wall opening. Within 100 the tumbler casing I provide a tumbler 29, adapted to rest upon the casing base, which is formed with a peripheral notch 30 adapted to be moved into alinement with the notch 28 of the tumbler casing and said tumbler 29 is also formed with a lug 31. A washer 32 adapted to lie directly upon the 110

tumbler 29 encircling the lug 31 is formed with the spaced outwardly projecting prongs 33 which project through the casing opening 25 to engage the anchor lug 23. A second tumbler 34 adapted to lie directly upon the washer 32 is formed with a peripheral notch 35 adapted to be moved into alignment with the notch 28 of the tumbler casing and said tumbler 34 is formed with the lug 36. A second washer 37 adapted to lie directly upon the tumbler 34 is formed with the spaced outwardly projecting prongs 38 which project through the casing opening 25 to engage the anchor lug 23. When the peripheral notches of the tumblers 29, 34 register with the casing opening 25 the anchor lug 23 may project into said alined notches and between the prongs of the washers to prevent independent rotary movement of one or more of said elements and due to this fact it is practically impossible for the relative position of the tumblers to become disturbed while the lock is open. The tumbler casing is capable of a sliding movement over the casing 21 and when the notched portions of the tumblers and of the tumbler casing are engaged by the anchor lug 23 the tumbler casing has moved into such position that its extension 27 is removed from the yoke 19. When the tumbler casing is moved out of engagement with the anchor lug 23 the extension 27 is again disposed within the yoke 19. The flange 12 fits snugly inside the periphery of the tumbler casing 24 and movement of the indicator 10 in the elongated slot 11 is sufficient to cause the said flange 12 to slide the casing 24 back and forth upon the bottom of the casing 21 to cause engagement with or disengagement from the lug 23.

When the notched portions of the tumblers and the casing opening 25 are in alignment, the indicator 10 may be moved to move the tumbler casing back and forth over the casing 21, as described, since the terminal flange 12 of said indicator fits snugly inside the rim of the tumbler casing. The lug 14 of the indicator projects toward the tumbler 34 inside the washer 35 for engagement with the lug 36, which projects from each lateral face of said tumbler, as the indicator is rotated. To determine a combination the indicator is rotated and when its lug 14 engages the lug 36 of tumbler 34 it will rotate that tumbler and the opposite end of lug 36 upon the opposite side of the tumbler coming in engagement with the lug 31 of the tumbler 29 will rotate tumbler 29. When the notch 30 of tumbler 29 is in alignment with the tumbler-opening 25, as may be determined by observation through the sight perforation 21^a, a reading of the indicator upon the graduations 7 is taken. The indicator is now rotated in the opposite direction thus rotating the tumbler 34 until its

notch 35 is in alinement with the notch 30 and opening 25 when another reading of the indicator upon the graduations 7 is taken. The direction in which the indicator is moved, during both movements, that is whether first to the right and then to the left, or vice versa, together with the readings taken, form the combination. When the notches 30, 35 and opening 25 are in alinement the tumbler casing 24 will slide away from the yoke 19 through gravity when the lock is in the position shown in Figs. 1 and 2, and this movement will also be shared by the indicator 10, and the tumblers will move into engagement with the anchor lug 23. The gravity movement just described will take place provided the lock is retained by the trunk, to which it is secured, in vertical position, which is usual. The lock is now open and in this position the tumblers are retained in their relative positions by the anchor lug so that the mechanism cannot become locked in open position. When the lock is open the casing 21 and leaf 4 are readily moved out of engagement with the yoke 19. To lock the lock the leaf and casing 21 are again moved into engagement with the yoke 19 and the indicator moved toward said yoke and then rotated when the notched portions of the tumblers will be disposed out of alinement with each other and with the opening 25 in the tumbler casing.

What is claimed is:—

1. In a lock, a hinged leaf formed with graduations and with an elongated perforation, a perforate casing carried by said leaf, one of the perforations in said casing being a "sight perforation," a winged plate formed with a depression to receive said casing, an inverted U-shaped yoke carried by said plate for disposal in one perforation in said casing, an anchor lug formed in said casing diametrically opposite the yoke-receiving perforation, a notched tumbler casing disposed in the first named casing, the notched portion thereof being in engagement with the said anchor lug, an extension formed upon said tumbler casing for releasable engagement with the said yoke, 100 notched tumblers within said tumbler casing, the notched portions of said tumblers being adapted for releasable engagement with said anchor lug, said tumbler casing being slidable relative to said first named 105 casing, in one position of the latter, through gravity to cause disengagement of said tumbler-casing-extension from said U-shaped yoke and engagement of the notched portions of the tumblers with said anchor lug, 110 a pronged washer arranged upon each tumbler within said tumbler casing, the prongs of said washers being spaced apart for engagement with the said anchor lug, lugs formed upon said tumblers for engagement 115

with each other, an indicator disposed in the elongated portion of said hinged leaf and formed of two cup-shaped portions each provided with a flange which flanges 5 are disposed upon opposite sides of said hinged leaf, one of said flanges fitting snugly inside the periphery of said tumbler casing whereby sliding movement of said tumbler casing may be manually effected, and a lug 10 formed in said last named indicator flange for engagement with one of the lugs of one of said tumblers.

2. In a lock, a hinged leaf formed with 15 graduations and with an elongated perforation, a perforate casing carried by said leaf, one of the perforations in said casing being a "sight perforation," a winged plate formed with a depression to receive said casing, a yoke carried by said plate for dis- 20 posal in one perforation in said casing, an anchor lug formed in said casing, a tumbler casing disposed in the first named casing in engagement with the said anchor lug, an extension formed upon said tumbler cas- 25 ing for releasable engagement with the said yoke, rotary tumblers within said tumbler casing capable of releasable engagement

with said anchor lug, said tumbler casing being slidable with relation to the first named casing, in one direction through 30 gravity when the lock is opened, to cause disengagement of said tumbler-casing-extension from said U-shaped yoke and engagement of said tumblers with said anchor lug, pronged washers arranged upon said tumblers, the prongs of said washers engaging said anchor lug, means whereby rotary movement of one tumbler is transmitted to the other tumbler, an indicator disposed in the elongated perforation in 40 said hinged leaf and engaging said tumbler casing whereby sliding movement of the same may be manually effected, and a lug carried by said indicator for operative engagement with one of said tumblers. 45

In testimony that I claim the foregoing as my own I have hereto affixed my signature in the presence of two subscribing witnesses.

JOHN I. STEEN.
